**18-SUBSTITUTED YOHIMBONE DERIVATIVES
AND PROCESS THEREFOR**

John Shavel, Jr., Mendham, and Harold Zinnes, Denville, N.J., assignors to Warner-Lambert Pharmaceutical Company, Morris Plains, N.J., a corporation of Delaware

No Drawing. Filed July 11, 1961, Ser. No. 123,106
7 Claims. (Cl. 260—288)

The present invention relates to new and novel 18-substituted derivatives of yohimbane of the formula

wherein R_1 is phenyl substituted with one or two electron withdrawing groups such as halogen, nitro, trifluoromethyl and the like, and R_2 is hydroxyl or keto. This invention also relates to a method of preparing these compounds and to the pharmaceutically acceptable non-toxic acid addition and quaternary ammonium salts thereof. Useful R_1 substituents include p-chlorophenyl, p-bromophenyl, p-fluorophenyl, p-trifluoromethylphenyl, 3,4-dichlorophenyl, p-nitrophenyl, m-nitrophenyl, o-nitrophenyl, m-chlorophenyl, 2,4-dinitrophenyl, o-bromophenyl and the like.

The compounds of this invention bear the A, B, C, D, and E rings as depicted in the above structural formula and are, generally, alkaloids of the yohimbane series. Depending upon the configuration of the hydrogen atom at the 3-position and the existence of cis or trans fusion of the D and E rings, four different configurations are possible, that is yohimbane, 3-epiyohimbane, allo-yohimbane and 3-epiallo-yohimbane. The present invention includes within its scope derivatives of these four families of alkaloids bearing

substituents at the 17 and 18 positions, respectively.

The compounds of this invention have interesting and significant pharmacological activity and are useful as anti-inflammatory agents. In addition, they are valuable intermediates in the production of other compounds of the yohimbane series. For example, heating the compounds of our invention bearing a keto group at the 17-position results in their dehydration to form compounds bearing a $=\text{CH}-\text{R}_1$ substituent at the 18-position. Such compounds are described and claimed in the application of John Shavel, Jr., George Bobowski and Maximilian von Strandtmann entitled "Yohimbane Derivatives and Process Therefor," Serial No. 123,119, filed concurrently herewith.

2

We have now found that the reaction of 17-ketoyohimbane alkaloids of the formula

15 either in the pure state or in the state in which they are obtained in the course of synthetic processes, with an aldehyde of the formula R_1-CHO at a temperature of about 20° C. to 40° C. results in the preparation of those compounds of our invention having the formula

20

25

30

wherein R_1 is as described hereinabove.

The reaction is carried out in an inert solvent such as methanol or ethanol in the presence of aqueous alkali, for example sodium hydroxide or potassium hydroxide. Upon completion of the reaction, which normally requires about 5 to about 40 hours, the precipitate, which constitutes the desired product, is purified by crystallization.

The compounds prepared as described above may be converted to compounds of the formula

45

50

55

by treatment with a reducing agent, for example lithium aluminum hydride, potassium borohydride, sodium borohydride, lithium tri-(tert-butoxy) aluminum hydride and the like at a temperature of 0° C. to 30° C. in an inert solvent such as methanol, ethanol, tetrahydrofuran and the like. At the conclusion of the reaction, which requires about 30 minutes to about 24 hours, the mixture is treated with water or dilute base and the precipitate is purified by crystallization.

The compounds of this invention may be converted into their pharmaceutically acceptable non-toxic acid addition or quaternary ammonium salts. Useful acid-addition salts are those formed with such acids as maleic, fumaric, benzoic, succinic, methylsulfonic, sulfonic, citric, tartaric, salicyclic, malic, cinnamic, hydrochloric, hydrobromic, phosphoric and the like. The acid addition salts may be prepared in the conventional manner, for example, by treating a solution or suspension of the free base in an organic solvent with the desired acid, and then recovering the salt which forms by crystallization techniques. The quaternary salts are prepared by heating a solution of the base in a suitable solvent with a reactive alkyl halide such as methyl iodide, ethyl bromide, n-hexyl bromide, benzyl chloride or another reactive ester such as methyl sulfate, ethyl sulfate or methyl p-toluenesulfonate.

For therapeutic use, the new and novel compounds of this invention, either as the free base or in the form of a pharmaceutically acceptable, non-toxic acid addition or quaternary ammonium salt, may be formulated with a conventional pharmaceutical carrier to form tablets, capsules, elixirs, solutions, suspensions, suppositories and the like.

The following examples are included in order further to illustrate the present invention:

EXAMPLE 1

18-(α -Hydroxy-p-Nitrobenzyl)Yohimbone

A mixture of 15 g. yohimbone, 25 g. p-nitrobenzaldehyde, 15 ml. 10% aqueous sodium hydroxide, and 400 ml. methanol is stirred at room temperature for ten hours and then allowed to stand at room temperature overnight. The crystals which form are recrystallized from acetonitrile to give 16.9 g. of product, M.P. 222-240° dec., $[\alpha]_D^{25} -93^\circ$ (pyridine, c.=0.62). Recrystallization from the same solvent gives pure 18-(α -hydroxy-p-nitrobenzyl)yohimbone, M.P. 218-220° dec., $[\alpha]_D^{25} -92^\circ$ (pyridine, c.=0.51).

Analysis.—Calc.: C, 70.09; H, 6.11; N, 9.43. Found: C, 70.13; H, 5.91; N, 9.43.

EXAMPLE 2

18-(α -Hydroxy-p-Chlorobenzyl)Yohimbone

A mixture of 15 g. yohimbone, 25 ml. benzaldehyde, 15 ml. 10% aqueous sodium hydroxide, and 450 ml. methanol is stirred at room temperature for twenty hours and then allowed to stand at room temperature overnight. The crystals which form are recrystallized from acetonitrile to give 12.2 g. of product, which melts at 208-214°, resolidifies and melts again at 275-280°; $[\alpha]_D^{25} -96^\circ$ (pyridine, c.=0.63). Recrystallization from acetonitrile gives pure 18-(α -hydroxy-p-chlorobenzyl)yohimbone which melts at 229-232°, resolidifies and remelts at 284-289°, $[\alpha]_D^{25} -94^\circ$ (pyridine, c.=0.5).

Analysis.—Calc.: C, 71.79; H, 6.26; N, 6.44; Cl, 8.65. Found: C, 71.84; H, 6.38; N, 6.33; Cl, 8.55.

EXAMPLE 3

18-(α -Hydroxy-3,4-Dichlorobenzyl)Yohimbone

A mixture of 10 g. yohimbone, 15 g. 3,4-dichlorobenzaldehyde, 15 ml. 10% aqueous sodium hydroxide, and 500 ml. methanol is stirred at room temperature for eighteen hours. An additional 5 g. 3,4-dichlorobenzaldehyde are added, the mixture is stirred six hours longer, and then is allowed to stand over-night at room temperature. The crystals which form are filtered off, washed with methanol, and dried in vacuo at 80° for 3 hours. Yield: 14.2 g., M.P. 207-209°, $[\alpha]_D^{25} -85^\circ$ (pyridine, c.=0.88). Recrystallization from acetonitrile gives 18-

(α -hydroxy-3,4-dichlorobenzyl)yohimbone, M.P. 219-221° dec., $[\alpha]_D^{25} -85^\circ$ (pyridine, c.=0.55).

Analysis.—Calc.: C, 66.52; H, 5.58; N, 5.97; Cl, 15.11. Found: C, 66.47; H, 5.73; N, 6.20; Cl, 15.08.

EXAMPLE 4

18-(α -Hydroxy-3,4-Dichlorobenzyl)Yohimbol

A mixture of 7 g. 18-(α -hydroxy-3,4-dichlorobenzyl)yohimbone, 6 g. potassium borohydride, and 150 ml. methanol is stirred at room temperature for two hours, showing that the reaction is complete. The methanol is removed by distillation in vacuo and the residue is triturated with 150 ml. water. The resulting precipitate is filtered off, washed with water, air dried, and recrystallized from methanol. Two recrystallizations yield 3 g. of 18-(α -hydroxy-3,4-dichlorobenzyl)yohimbol as a mono-methanolate, M.P. 253-255° dec., $[\alpha]_D^{25} -101^\circ$ (pyridine, c.=0.63).

Analysis.—Calc.: C, 64.41; H, 6.41; N, 5.56; Cl, 14.09. Found: C, 64.50; H, 6.35; N, 5.68; Cl, 13.95.

Throughout the specification, all temperatures are given in degrees centigrade.

It is understood that the foregoing detailed description is given merely by way of illustration and that many variations may be made therein without departing from the spirit of our invention.

Having described our invention, what we desire to secure by Letters Patent is:

30 1. A member selected from the group consisting of compounds of the formula

wherein R_1 is phenyl substituted with one to two members selected from the group consisting of halogen, nitro and trifluoromethyl and R_2 is a member selected from the group consisting of keto and hydroxyl, and the pharmaceutically acceptable non-toxic acid addition and quaternary ammonium salts thereof with a compound selected from the group consisting of methyl iodide, ethyl bromide, n-hexyl bromide, benzyl chloride, methyl sulfate, ethyl sulfate and methyl p-toluenesulfonate.

55 2. 18-(α -hydroxy-p-nitrobenzyl)yohimbone.
3. 18-(α -hydroxy-p-chlorobenzyl)yohimbone.
4. 18-(α -hydroxy-3,4-dichlorobenzyl)yohimbone.
5. 18-(α -hydroxy-3,4-dichlorobenzyl)yohimbol.
6. A method of preparing compounds of the formula

wherein R_1 is phenyl substituted with one to two members selected from the group consisting of halogen, nitro

and trifluoromethyl which comprises treating a compound of the formula

with an aldehyde of the formula R_1-CHO at a temperature of about $20^\circ C.$ to about $40^\circ C.$ in an inert solvent in the presence of aqueous alkali.

7. A method according to claim 6 wherein said inert solvent is methanol and said alkali is sodium hydroxide.
